ABSTRACT OF THE DISCLOSURE

An electronically controlled switching network comprising matrices having multi-wire rows including line-wires, a principal control wire and a supplementary control wire, multi-wire columns including line-wires and a control wire, and crosspoints formed by line reed relays respectively connected between a row line-wire and a column line-wire, a control reed relay and a common energizing and holding winding for said line and control reed relays, the control reed relay and the common winding being serially connected between said principal row control wire and said column control wire and the point of junction of said control reed relay and common winding being connected to the supplementary row control wire. Connection signals are selectively applied between one supplementary row control wire and one column control wire of the matrix through a common winding and holding signals are selectively applied between one principal row control wire and one column control wire through the operated control reed relay and the common winding.

The present invention relates to electronically controlled electromechanical switching networks and more particularly to switching networks wherein the crosspoints are constituted by a plurality of reed relays having a common energizing winding.

In particular, through the article by H. Schonemeyer entitled "The experimental Stuttgart Exchange, first application of the quasi-electronic HE60 switching system" and published in the "Revue des Télécommunications" vol. 32, No. 2 (1964) pages 253 to 270, switching networks are known which comprise matrices, the crosspoints of which are constituted by pluralities of reed relays having a common energizing winding. These crosspoints are controlled by reed relays associated with the rows and columns of said matrices and the response time of which is added to that of the reed relays constituting the crosspoints. Since the wear of the reed relays depends on the number of times their contacts are opened and closed and since the relays associated with the rows and with the columns of a matrix operate far more frequently than those which constitute the crosspoints thereof, the life of the former is much shorter than that of the latter. Moreover, in the switching network described this article, the tests for the availability of routes are effected by means of reed relays, the rate of operation of which is of the same order and the life of which is as limited as those of the reed relays controlling the crosspoints.

One object of the invention is to provide switching networks comprising matrices, the crosspoints of which are reed relays wherein the duration of the connection and disconnection operations at a crosspoint in the matrix is limited substantially to the response time of the reed relays which constitute it.

Another object of the invention is to provide a switching network with reed relays, the component members of which have a life of the same order.

One feature of the switching network of the invention

2

is that the points of its switching matrices consist of pluralities of reed relays having a common energizing winding controlled directly by electronic means.

Another feature of the switching network of the invention is that each crosspoint comprises a reed relay serving as a holding contact for all the reed relays which constitute it.

Another feature of the switching network of the invention is that it comprises means for applying, to the energizing winding of each crosspoint, an operating current, means for applying to the energizing winding of an operated crosspoint, a holding current by means of said reed relay serving as a holding contact, and means for regulating independently the values of the operating and holding currents.

Another feature of the switching network of the invention is that shunt circuits for the surges due to the variations in current in the energizing windings of the crosspoints are established through diodes at the inputs to each matrix in such a manner that the electronic means controlling the crosspoints are protected from these surges and the noises which they cause through crosstalk are reduced.

One feature of the switching network of the invention is that the energizing windings for the crosspoints used in a connected route are fed in series by the holding current in such a manner that their connections between matrices can serve as test wires and that one end of said route can be identified by causing a variations in the holding current at its other end.

These features and advantages will be more clearly apparent, together with others, on reading the following description and examining the accompanying drawings in which:

35 FIGURE 1 is a diagram of a crosspoint with three reed relays and electronic control circuits in a matrix of a switching network according to the invention, and

FIGURE 2 illustrates diagrammatically a switching network with three matrices according to the invention.

40 FIGURE 1 shows a crosspoint with three reed relays 1₁₁, 2₁₁, 3₁₁ of a switching matrix 100, an operating circuit for this crosspoint comprising two transistors 41, 42 respectively controlled by a control row address register 44 and a control column address register 45, and a release 45 circuit comprising a transistor 43 controlled by a release row address register 46.

The connection matrix 100 is a triple matrix comprising triple rows such as 21₁, 22₁, 23₁ and triple columns such as 11₁, 12₁, 13₁, the crosspoints of which are constituted by

50 groups of three reed relays such as 1₁₁, 2₁₁, 3₁₁ having a common control winding 32₁₁. Two of the reed relays in each group, for example 2₁₁ and 3₁₁ respectively connect the columns 12₁, 13₁ and the rows 22₁, 23₁ associated with the two line wires of a telephone line and the reed relay 55 1₁₁ which constitutes the holding contact of the crosspoint connects the column 11₁ to one end 33₁₁ of the winding 32₁₁, the other end of which is connected to the line 21₁. The point 33₁₁, which is common to the reed relay 1₁₁ and to the winding 32₁₁, is connected by means of a diode 31₁₁ and a resistor 30 of value R₁, to the collector of the transistor 42. This is a p-n-p transistor which is controlled through its base through the output from column address register 45 associated with the column 11₁ and the emitter of which is connected to ground; its collector is connected

60 through a bias resistor 47, shunted by a reverse diode 48, to the negative terminal, for example at -12 v., of a voltage source 35 having its midpoint connected to ground. The transistor 41 is an n-p-n transistor controlled through its base by the output from control row address register 44 associated with the row 21₁ having its emitter connected to the negative terminal of the voltage source 70

35 and its collector connected to the row 21₁. The transistor 43 is likewise of the n-p-n type; its base is connected to the output of release row address register 46 associated with the row 21₁, its emitter is connected to ground and its collector is connected, by means of a diode 50, to the row 21₁, itself connected to the positive terminal at +12 v. of the voltage source 35, through a reverse diode 49. Furthermore, the column 11₁ is connected to the same positive terminal of the source 35 through a resistor 40 of value R₂.

In the normal condition, the transistors 41, 42 are cut off, the transistor 43 is saturated and the diode 31₁₁ is blocked by the negative potential which is transmitted thereto through the resistors 47 and 30 in such a manner that no current can circulate in the windings 32₁₁ and that the reed relays 1₁₁, 2₁₁, 3₁₁ remains inoperative.

In order to operate the triple crosspoint, control pulses are applied simultaneously and respectively by the registers 44 and 45, at the time t₀ to the bases of the transistors 41 and 42. These become saturated, the diode 31₁₁ is unblocked, and the appearance, at the two terminals of the winding 32₁₁, of the pulses obtained, gives rise to a current there which circulates in the direction from the access 33₁₁ to the access 21₁, and becomes established in accordance with a transient phenomenon in a time t₁ which is a function of the inductance L₁ and of the resistance r₁ of the winding 32₁₁, and of the value R₁ of the resistor 30. At the end of the time t₁, this current reaches the value 12 v. / (R₁ + r₁) which is sufficient to operate the three reed relays 1₁₁, 2₁₁, 3₁₁ through the path, ground, saturated transistor 42, resistor 30, diode 31₁₁, winding 32₁₁, saturated transistor 41, -12 v.

The operation of the relay 1₁₁ causes the appearance, in the winding 32₁₁, of a second current having a value substantially equal to 24 v. / (R₂ + r₁) which is temporarily superimposed on the operating current in the same direction through the route +12 v., resistor 40, column 11₁, reed relay 1₁₁, winding 32₁₁, row 21₁, saturated transistor 41, -12 v. and then drops by half to the value 12 v. / (R₂ + r₁) when the control pulses leaving the registers 44 and 45 come to an end, and the transistors 41 and 42 are cut off and unblock the diode 50, which closes its circuit to earth through the saturated transistor 43, at the same time as they cut the operating circuit.

The value R₂ of the resistor 40 is selected in such a manner that the intensity 12 v. / (R₂ + r₁) of the holding current is sufficient to hold the reed relays 1₁₁, 2₁₁, 3₁₁ operated.

The disconnection of the crosspoint is obtained by applying a cut-off pulse, originating from the release row address register 46, to the base of the transistor 43, the cutting off of which interrupts the return to ground of the holding circuit and reconnects this to the positive terminal of the source 35 by means of the diode 49. The transient current which then arises in the winding 32₁₁ as a result of its inductance and travels through the circuit passing through the row 21₁, the diode 49, the resistor 40, the column 11₁ and the reed relay 1₁₁ to be closed through the winding 32₁₁, temporarily holds the relays 1₁₁, 2₁₁, 3₁₁ operated.

The law of decay of this transient current depends on the time constant L₁ / (R₂ + r₁). When the relay 1₁₁ opens, the new law of decay of this current depends on the time constant L₁ / (R₁ + r₁), the circuit established to the terminals of the coil 32₁₁ then being closed through the source 35, by the row 21₁ and the diode 49 on the one hand and the diode 48, the resistor 30 and the diode 31₁₁ on the other hand.

As will be seen, since the break current of the coil 32₁₁ always finds a closed circuit to flow away through, it cannot start any sparking between the stems of the relay 1₁₁ when their contact is opened.

In order to avoid unnecessary overloading of the drawing, only a single one of the crosspoints in the matrix 100 has been illustrated in FIGURE 1 it being understood that, in accordance with conventional arrangements, the transis-

tor 42, the resistor 30 and the resistor 40 may be common to all the crosspoints associated with one and the same column and the transistors 41 and 43 may be common to all the crosspoints associated with one and the same row.

FIGURE 2 illustrates, by way of non-limiting example, a chain consisting of three identical matrices 101, 102, 103 which are identical with the matrix 100 in FIGURE 1 and the interconnection of which enables two channels A and B to be connected to one another, each having three wires, comprising two line wires and one control and test wire.

The members common to FIGURES 1 and 2 are designated by the same reference numerals with the addition to their index, in FIGURE 2, of an additional digit 1, 2 or 3 according to whether these members are associated with the matrices 101, 102 or 103.

At the end A, the line wires are connected to the rows 22₁₁, 23₁₁ of the matrix 101 and the control wire to its row 21₁₁. The columns 11₁₁, 12₁₁, 13₁₁ of the crosspoint selected in the matrix 101 to ensure the connection, are connected to the rows 21₁₂, 22₁₂, 23₁₂, in the matrix 102 and the columns 11₁₂, 12₁₂, 13₁₂ of the crosspoint selected in the matrix 102 are connected to the rows 21₁₃, 22₁₃, 23₁₃ in the matrix 103. The columns 11₁₃, 12₁₃, 13₁₃ of the crosspoint selected in the matrix 103 are connected respectively to the control and line wires of the channel B.

Associated with each triple row in the matrix 101 are connection transistors 41 and disconnection transistors 43 which are controlled individually by the control row address register 44 and release row address register 46 and associated with each triple column in the matrices 101, 102, 103 are transistors 42₁, 42₂, 42₃, associated with individual outputs of control column address registers 45₁, 45₂, 45₃ and resistors 30₁ of value R₁₁, 30₂ of value R₁₂ and 30₃ of value R₁₃. Associated with the first wire 11₁₃ of each column in the matrix 103 is a resistor 40 which connects it to the positive terminal of the source 35 and the first wire 11₁₁, 11₁₂ of each column in the matrices 101, 102 is connected to the two terminals of the source 35 through reverse diodes 61₁, 62₁ and 61₂, 62₂. Magnetic cores 81₁₁, 82₁₂, 83₁₃, the control and reading circuits of which are not illustrated, enable the passage or the absence of current to be detected in the columns such as 11₁₁, 11₁₂, 11₁₃ in the matrices 101, 102, 103 in order to seek the available routes between the channels A and B for example through the three matrices 101, 102, 103 as is known, in particular, from the article by Jean Duquesne and Michel Rouzier entitled "A Connection Network for an Electronic Telephone Exchange" which appeared in the French periodical "l'Onde Electrique" No. 455, February 1965, pages 195 to 211. Moreover, magnetic cores 91₁₁ associated with each of the rows 21₁₁ in the matrix 101 enable the identification of the channel A which is connected, through the three matrices, to a column such as 11₁₃ in the matrix 103 by short-circuiting of the resistor 40 connecting said column to the positive terminal of the source 35, by means of transistors such as 73 controlled by an identification control register 70. An identification response register 71, the inputs of which are connected to the columns such as 11₁₃ in the matrix 103 by means of diodes such as 72 enable the channel B to be identified which is connected to a channel A, to the row line 21₁₁ of which there is applied a negative pulse, unblocking the associated transistor 41 by means of the register 44.

When a route such as that illustrated on FIGURE 2 between two channels A and B is available, the n-p-n transistors 41 and p-n-p transistors 42₁, 42₂, 42₃ and the diodes 31₁₁₁, 31₁₁₂, 31₁₁₃ are blocked, the n-p-n transistor 43 is saturated and the contacts of the reed relays 1₁₁₁, 2₁₁₁, 3₁₁₁, 1₁₁₂, 2₁₁₂, 3₁₁₂ and 1₁₁₃, 2₁₁₃, 3₁₁₃ are open.

The operation of the crosspoints of the matrices 101, 102, 103, is effected in turn by coincidence between the unblocking of the transistor 41 and that of each of the

transistors 42_1 , 42_2 , 42_3 in succession. For this purpose, a time base, not illustrated, controls the moments of the beginning and end of the application of unblocking pulses to these transistors by the address registers 44 , 45_1 , 45_2 and 45_3 respectively. These moments are calculated as a function of the inertia of the reed relays and of the time constants of their control circuits.

At the moment t_0 , the registers 44 and 45_1 simultaneously unblock the transistors 41 and 42_1 of which the first applies a negative pulse (from 0 to -12 v.) to one end of the winding 32_{111} through the row 21_{11} , and of which the second applies a positive pulse (from -12 v. to 0) to the other end 33_{111} of the winding 32_{111} , through resistor 30_1 and diode 31_{111} . The resulting current only reaches its nominal operating value 12 v./($R_{11}+r_{11}$) at the end of a time $t_1-t_0=L_{11}/(R_{11}+r_{11})$, L_{11} being the inductance of the winding 32_{111} and r_{11} its resistance. Since the reed relays 1_{11} , 2_{11} , 3_{11} have a certain inertia, their contacts only close at a moment t_2 .

The register 45_2 , then unblocks the transistor 42_2 which becomes saturated and applies a positive pulse (from -12 v. to 0) to the end 33_{112} of the winding 32_{112} of the matrix 102 , while the voltage -12 v. applied by the saturated transistor 41 to the row 21_{11} is transmitted by the winding 32_{111} , the reed relay 1_{111} , the column 11_{11} , and the row 21_{12} of the matrix 102 to the other end of the winding 32_{112} . A current therefore develops in this winding in accordance with a transient phenomenon depending on the time constant

$$t_3-t_2=(L_{11}+L_{12})/(R_{12}+r_{12}+r_{11})$$

and is superimposed, in the winding 32_{111} of the matrix 101 , on the operating current which had been established there since the time t_1 .

Thus at the time t_3 , the current in the winding 32_{111} reaches an intensity substantially double that which it had from t_1 to t_2 . The register 45_1 then cuts off the transistor 42_1 which tends to restore the intensity of the current in the winding 32_{111} to its previous value and the decreasing transient current which results finds a conducting path through the saturated transistor 41 , the diode 62_1 and the reed relay 1_{111} .

At the same moment, the operating current having a value 12 v./($R_{12}+r_{12}+r_{11}$) established in the winding 32_{112} operates the reed relays 1_{112} , 2_{112} , 3_{112} . This operation takes place with a certain inertia from the time t_3 to the time t_4 . The register 45_3 then unblocks the transistor 42_3 which becomes saturated and applies a positive pulse (from -12 v. to 0) to the end 33_{113} of the winding 32_{113} of the matrix 103 while the voltage -12 v. applied by the saturated transistor 41 to the row 21_{11} of the matrix 101 is transmitted by the winding 32_{111} , the reed relay 1_{111} , the column 11_{11} , the row 21_{12} of the matrix 102 , the winding 32_{112} , the reed relay 1_{112} , the column 11_{12} and the row 21_{13} of the matrix 103 , to the other end of the winding 32_{113} . A current therefore arises in this winding in accordance with a transient phenomenon dependent on the time constant

$$t_5-t_4=(L_{11}+L_{12}+L_{13})/(R_{13}+r_{13}+r_{12}+r_{11})$$

and is superimposed, in the windings 32_{111} and 32_{113} of matrices 101 and 103 , on the operating current which had become established there during the time t_3 . At the time t_5 , since the current in the windings 32_{111} , 32_{112} has a value substantially double that which it had from t_3 to t_4 , the register 45_2 cuts off the transistor 42_2 which tends to restore this current to its previous value and the decreasing transient current which results finds a conducting path through the reed relay 1_{111} , the winding 32_{111} , the saturated transistor 41 , the diode 62_2 and the reed relay 1_{112} . At the same moment, the operating current of value 12 v./($R_{13}+r_{13}+r_{12}+r_{11}$) established in the winding 32_{113} operates the reed relay 1_{113} , 2_{113} , 3_{113} . This operation takes place with a certain inertia from the time t_5 to the time t_6 at the time t_6 , the register 44 cuts off the transistor 41

which has the effect of unblocking the diode 50 and of thus bringing the row 21_{11} of the matrix 101 to ground potential by means of the saturated transistor 43 and the register 45_3 cuts off the transistor 42_3 which has the effect of restoring the potential of the column 11_{13} of the matrix 103 to $+12$ v. through the resistor 40 having a resistance R_2 . The holding current thus established has the value of

$$12 \text{ v.}/(R_2+r_{11}+r_{12}+r_{13})$$

Since the nominal operating currents in the windings 32_{111} , 32_{112} , 32_{113} have respective values, with a voltage of 12 volts, of

$$12/(R_{11}+r_{11}) \text{ (from the time } t_1 \text{ to the time } t_2)$$

$$12/(R_{12}+r_{12}+r_{11}) \text{ (from the time } t_3 \text{ to the time } t_4)$$

$$12/(R_{13}+r_{13}+r_{12}+r_{11}) \text{ (from the time } t_5 \text{ to the time } t_6)$$

and it is possible to give them the same value by taking

$$R_{12}+r_{12}=R_{11}$$

$$R_{13}+r_{13}+r_{12}=R_{11}$$

that is to say:

$$R_{12}=R_{11}-r_{12}$$

$$R_{13}=R_{11}-r_{12}-r_{13}=R_{12}-r_{13}$$

25 The holding current may have the same value as the operating current if R_2 is taken equal to R_{13} or a different value which is defined by the type of reed relay used.

The disconnection of the interconnected crosspoints is obtained by a control pulse emitted by the release register 30 46 and applied to the base of the transistor 43 . This is cut off and interrupts the holding current of three windings 32_{111} , 32_{112} , 32_{113} in series where a variable current arises, the law of decay of which depends on the time constant:

$$L_{11}+L_{12}+L_{13})/(R_2+r_{11}+r_{12}+r_{13})$$

With regard to the identification of the end A of a connected route, that is to the search of a channel A connected to a given channel B, a positive pulse is transmitted by the identification control register 70 through its terminal associated with the channel B considered to

40 transistor 73 which becomes saturated. The magnetic core 91_{11} inserted in one of the wires of the channel A is so designed as not to be responsive to the holding current, but only to the positive surge in said holding current due

45 to the changeover of transistor 73 . Accordingly, magnetic core 91_{11} changes over. Diode 72 prevents the identification response register 71 from being actuated. With regard to the identification of the end B of a connected route, that is to the search of a channel B connected to a given

50 channel A, a positive pulse is transmitted by row address register 44 through its terminal associated with the channel A considered to transistor 41 which becomes saturated. A negative pulse is applied to the row 21_{11} of the matrix 101 , which pulse is transmitted to the identification response register 71 by the connected route and the diode 72 associated with the column 11_{13} of said route.

What we claim is:

1. A switching network comprising matrices having 60 rows including line-wires, a principal control wire and a supplementary control wire, columns including line-wires and a control wire, and cross-points each formed by line reed relays respectively connected between a row line-wire and a column line-wire, a control reed relay

65 and a common energizing and holding winding for said reed relays, said control reed relay and common winding being serially connected between said principal row control wire and said column control wire and the point of junction of said control reed relay and common winding 70 being connected to said supplementary row control wire, means for selectively applying between said supplementary row control wires and said

75 column control wires energizing signals for energizing the winding and operating the relays of a crosspoint and means for selectively applying between said principal row control wires and said

column control wires holding signals for energizing the winding of said crosspoint through its operated control reed relay.

2. A switching network comprising a plurality of cascade-connected matrices, each having rows including line-wires, a principal control wire and a supplementary control wire, columns including line-wires and a control wire, and crosspoints each formed by line reed relays respectively connected between a row line-wire and a column line-wire, a control reed relay and a common energizing and holding winding for said reed relays, said control reed relay and common winding being serially connected between said principal row control wire and said column control wire and the point of junction of said control reed relay and common winding being connected to said supplementary row control wire, means for cascade-connecting the line-wires and the control wire of the columns of a matrix respectively to the line-wires and to the principal control wire of the rows of the subsequent matrix, means for selectively applying in time succession between

the column control wires of the first matrix on the one hand and the supplementary row control wires of the successive matrices on the other hand time-shifted energizing signals for energizing the winding and operating the reed relays of a crosspoint in each matrix, and means for selectively applying between the principal row control wires of the first matrix on the one hand and the column control wires of the last matrix on the other hand holding signals for serially energizing the windings of said crosspoint in each matrix through the operated control reed relay comprised in said crosspoint.
